TYPEWRITING MACHINE

Frederick A. Hart, Stamford, Conn., assignor to
 Remington Typewriter Company, Ilion, N. Y.,
 a corporation of New York

Application November 19, 1931, Serial No. 576,066

2 Claims. (Cl. 235—59)

My invention relates to typewriting machines, and more particularly to combined typewriting and computing machines.

Previous to this invention it was necessary, when operating a power driven combined typewriting and computing machine such as is disclosed in my application Serial No. 510,941, for the operator to actuate the numeral keys more slowly than the alphabet keys. The reason for this was that the numeral keys at times had to actuate a computing mechanism before they actuated their numeral printing type bars. On the other hand, the alphabet keys did not have to actuate anything except their associated type bars with the result that the carriage escapement mechanism could be actuated at the exact moment when an alphabet type bar struck the printing platen. Because the alphabet keys had no other duties than to actuate their type bars, they were operated from a snatch roll and it was found that the carriage would escape toward the left and settle in its position of rest in such timed relation to the next succeeding alphabet key depression that the operator could manipulate the keys in an even and speedy manner, and even with long and heavy carriages, the alphabet printing was not slowed up appreciably. However, the numeral keys had to both actuate a computing mechanism and numeral type bars and they had to actuate the computing mechanism before actuating the numeral type bars. Because of this the snatch roll was not used here but instead power driven cams were used. These cams operated the computing mechanism during the first half of their cycles and then operated the numeral type bars. Both the numeral type bars and the alphabet type bars operated a common universal bar which, in turn, operated a common carriage escapement mechanism but it was found that the carriage escapement mechanism was operated later in the cycle of operation of a numeral key than in the cycle of operation of an alphabet key. The result was that the carriage did not escape toward the left and come to a position of rest as soon after the depression of a numeral key as it did after the depression of an alphabet key and consequently, especially when long, heavy carriages were used, it was found that if the master dog of the computing mechanism were to operate correctly, the time between successive numeral key depressions would have to be greater than the time between successive alphabet key depressions. Consequently, the operator was annoyed by the change in cadence which she was forced to make when

writing letters and then numerals and vice versa. It is, therefore, the main object of this invention to even the cadence of the manual key manipulation in the above mentioned machine, so that the machine operator may concentrate upon her bookkeeping and typewriting without being worried by eccentric key depression timing.

To the above and other ends which will hereinafter appear, my invention consists in the features of construction, arrangements of parts and combinations of devices set forth in the following description and particularly pointed out in the appended claims.

In the accompanying drawings wherein like reference characters indicate corresponding parts in the different views—

Fig. 1 is a skeletonized, vertical, fore and aft sectional view of a combined typewriting and computing machine embodying my invention.

Fig. 2 is an enlarged, detail, fragmentary, perspective view of a portion of the motion transmitting connections to the escapement mechanism.

Fig. 3 is an enlarged, detail, fragmentary, sectional view of the same, taken on the line 3—3 of Fig. 1 and looking in the direction of the arrows at said line.

Figs. 4 and 5 are enlarged, detail, fragmentary, transverse sectional views of the same, taken respectively on the lines 4—4 and 5—5 of Fig. 1, and looking in the direction of the arrows at said lines.

Fig. 6 is an enlarged, detail, fragmentary, perspective view of the universal bar controlled by the actuation of the numeral type bar operating means, together with some of the associated parts.

Fig. 7 is an enlarged, detail, fragmentary, vertical sectional view showing some of the parts illustrated in Fig. 6.

The present invention is in the nature of an improvement on the power actuated combined typewriting and computing machine disclosed in my application Serial No. 510,941 filed January 24, 1931, and which is shown in part in the accompanying drawings.

In said machine each numeral printing type bar does not receive its printing stroke until after the computing mechanism has been actuated, and the carriage escapement mechanism is actuated by the numeral printing type bars and such actuation of the escapement mechanism does not take place until the last portion of the printing stroke of a numeral printing type bar. It follows therefore that very little time intervenes

between the "let-off" of the carriage and impact of the actuated numeral printing type bar. It is of course necessary that the carriage shall receive its letter space advance in proper timed relation to the printing and computing operation. Otherwise, the usual lock for the carriage, controlled by the computing mechanism, will not function properly and the machine will be tied up, or the parts will not function as intended. These defects do not occur when machines are equipped with carriages up to a certain length, or when the numeral keys are not rapidly operated. However, when longer carriages are employed and the machine is very rapidly operated, the step-by-step letter-space advance of the carriage is more sluggish than it would be with a lighter carriage and requires more time to overcome inertia. As a result, either an improper operation or a tying up of the machine would follow, or the operator would be compelled to decrease the speed of operation.

It is a purpose of the present invention to overcome these difficulties and to insure the proper advance of the carriage under a rapid operation of the machine whether a relatively short or a relatively long carriage is employed.

While I have shown my invention embodied, in the present instance, in a "Remington electrified bookkeeping machine," such as is disclosed in my above entitled application, it should be understood that the invention is not restricted to use in such machine but may be employed in typewriting, or combined typewriting and computing, machines generally, wherever found available.

I will first describe the above mentioned Remington machine, or so much thereof as is deemed necessary to arrive at an understanding of my invention in its embodiment therein.

40 A series of key levers 10 for the alphabet printing type bars 11 are fulcrumed on a fulcrum bar 12. Each key lever 10 is provided with a finger key 13 and is returned to normal position by a returning spring 14. Each lever 10 has a depending arm 15 that coacts with an angular trip lever 16 that carries an engaging member 16a. Each member 16a coacts with a pawl 17 to throw the engaging nose 18 thereof into the path of teeth 19 on a constantly running snatch roll 20. 45 The snatch roll extends longitudinally beneath the various key levers and is continuously driven from a suitable motor (not shown), as illustrated in my above mentioned application. Each pawl 17 is pivoted to and carried by a lever 21 fulcrumed on the bar 12 and arranged beside the companion key lever 10. Each lever 21 has an upstanding lug or arm 22 that carries a laterally projecting pin 23 received in a slot in the forwardly extending arm of a companion angular lever 24 mounted to turn on a fixed pivot rod 24a. The upper end of each lever 24 carries a laterally projecting pin which is received and works in a slot in the heel of the companion type bar 11 to move it to printing position.

50 60 65 70 75 The heel of each alphabet printing type bar 11 is provided with a cam 25 that coacts with a universal bar 26 mounted for movement fore and aft of the machine. Motion is transmitted through arms 27 on the universal bar 26 to upper arms 28 and through said arms 28 to a rock shaft 29 from which said arms 28 project. A third arm 30 extends upward from the shaft 29 and is located intermediate the arms 28. The upper end of the arm 30 is bifurcated and a pin 31 extends across the space between the arms

forming the bifurcation. This pin is received in the bifurcated end of a horizontally disposed link 32, the rear end of which is bifurcated to straddle a headed pin 33 that projects from the lower end of a dog rocker 34. The dog rocker is pivoted at 35 and carries the usual normally engaged loose dog 36 and a holding dog 37. These dogs coact with an escapement wheel 38 operatively connected with a feed pinion 39 that meshes with the usual feed rack 40 carried by the carriage 41. The carriage is of the usual construction and is mounted to travel over the top plate 42 from side-to-side of the machine under the power of the usual spring drum, not shown.

15 It will be understood that at each depression of an alphabet printing key 13 the corresponding pawl 17 will be moved into engagement with the continuously running snatch roll 20, which will result in carrying down the companion lever 21 and actuating the companion type bar 11. The engaged pawl 17 continues to descend until it is disengaged from the snatch roll by an abutment 17a arranged in the path of the pawl. When the actuated type bar 11 in its printing stroke reaches some such position as that indicated in dotted lines in Fig. 1, the cam 25 will have coacted with the universal bar 26 and shifted the dog rocker to start the operation which results in a "let-off" of the carriage, although a letter space movement of the carriage is not effected or completed until the dog rocker returns to normal position under the force of an independent spring (not shown) during the return of the actuated type bar.

25 30 35 40 45 50 55 60 65 70 75 80 85 90 95 In Remington machines the control of the dog rocker from the space key 43 is effected by a crank arm 44 (Fig. 1) that coacts with the lower end of a lever 45, pivoted at 46 on a fixed bracket 47. The upper arm of the lever 45 stands in front of a laterally projecting lug 48 on the link 32 as shown in Figs. 2 and 3. A depression of the space key 43 results in a clock-wise movement of the lever 45 as the parts are shown in Fig. 1, which moves the link 32 rearward and actuates the dog rocker. When the space key returns to normal position a spring 49 is effective to return the lever 45 to normal position, the independent spring (not shown) returning the dog rocker. In the movement of the dog rocker by the space key the link 32 will move fore and aft of the machine independently of the universal bar 26, due to the pin and slot connection 31, 32 between said link and the universal bar, or its operating connections.

55 60 65 70 75 80 85 90 95 Each of the numeral printing type bars 58 and the computing mechanism are actuated by power actuated means that are separate and distinct from the snatch roll 20 by which the alphabet printing type bars are actuated. This is also true of the means for controlling the escapement mechanism during the actuation of a numeral printing type bar, as will be understood from the description of such parts now to be given.

65 70 75 80 85 90 95 As in the above mentioned Remington electrified machine there is provided a continuously running, motor driven, shaft 51 on which are loosely mounted a series of cams 52 corresponding in number to the numeral printing type bars. 70 Associated with each cam 52 is a locking wheel 53 fixed on the shaft 51 beside the companion cam. A locking latch 54 is pivoted to each cam, and a spring (not shown) tends to press the latch into locking engagement with its companion.

locking wheel 53 to lock or couple the cam to turn with the shaft during a single revolution of the cam. A trip member 55 is associated with each latch 54 and when in engagement therewith, as indicated in Fig. 1, maintains the latch against the force of its spring out of engagement with the companion locking wheel, so that the cam thus engaged is held against movement while the shaft 51 revolves independently thereof.

10 Cooperative with each trip 55 is a depending arm 56 pivoted at 57 on an associated numeral key lever 58. These levers 58 are fulcrumed on the fulcrum bar 12 and each is provided with a finger key 59 and a returning spring like the spring 14. 15 At the depression of any numeral key 59 the associated trip 55 is turned anti-clockwise against the force of its returning spring 60 to release the companion latch 54 and enable it to engage the associated locking wheel 53 and thus lock the companion cam to revolve with the shaft 51. Before the depressed key lever 58 reaches the bottom of its stroke, its arm 56 slips off the companion trip 55 enabling it to return independently of the key lever to normal position. In such position the 20 trip is in the path of the companion latch 54 so that when the companion cam 52 makes one revolution the latch will be engaged by its trip 55 and moved against the force of its spring to release it from the locking wheel with which it 25 was engaged.

Each revolution of a cam 52 brought about in the manner described is effective to first operate the computing mechanism and then effect a printing movement of the companion numeral printing type bar, as will now be described.

30 A series of oscillatory actuating arms or members 61 corresponding in number to the cams 52 are pivoted on a pivot rod 62. Each arm 61 carries a roller 63 which bears on the periphery 40 of the associated cam 52. A spring 64 coacts with each arm 61 to force it towards the shaft 51, and the effective force of each spring is sufficient to actuate the computing mechanism when the arm is lowered under control of its cam. Connected to the rear end of each arm 61 is an upright link 65 which in turn is connected to a pivoted arm 66. Each of these arms 66 is pivoted to an upwardly extending link 67. Each link 67 is connected to a "fan" 68 of the actuator for the 45 computing mechanism. For the purposes of the present invention the computing mechanism from and above the links 67 may be the well known Wahl mechanism used in manually actuated Remington machines and is substantially the same as that disclosed in the patent to Wahl No. 55 1,270,471 dated June 25, 1918. Such computing mechanism may be the same as that disclosed in my above mentioned application which involves some improvements that need not be disclosed or 60 considered for the purposes of the present invention.

It is unnecessary to further describe this computing mechanism except to point out at this time that it involves a locking member or dog 69 that is automatically thrown into engagement with a rack 70 (connected with the typewriter carriage) at each computing operation or at each downward movement of an arm 61. Unless the timed relation in the movement of the carriage to that of the locking dog 69 is accurate then a faulty operation or possibly a tying up of the machine will result. As hereinbefore indicated it is one of the purposes of the present invention to prevent such faulty operation or tying up of the machine.

With the foregoing explanation I will proceed with the description of the construction, it being understood that on the first half revolution of any of the cams 52 the associated arm 61 will be lowered to operate the computing mechanism and turn the master wheel 71 and the wheel 72 in the vertical totalizer 73 which is in mesh therewith, such operation taking place by the force of the companion spring 64 operating on the actuated arm 61.

10 Up to this time the companion numeral printing type bar has not been actuated. But as the driven cam 52 completes the second half of its revolution the companion arm 61 will be positively returned by the cam to normal position against the force of its spring 64, and it is at this time that the companion numeral printing type bar is actuated, as will now appear.

The rear end of each arm 61 has a trip or one-way operating device 74 pivoted thereto at 75 20 and spring-pressed to its normal position against a suitable stop 76 on the companion arm 61 by a spring 77. The trips 74 coact with a series of actuating levers 78 pivoted on a pivot rod 79. Each trip device 74 in the downward movement 25 of its companion arm 61 coacts with the forward end of the associated lever 78 and is turned thereby against the force of the associated spring 77 without at this time communicating any motion to the cooperative lever 78. When, however, the 30 lowered trip 74 passes the forward end of its companion lever 78, said trip will be forced by its spring beneath the forward end of said lever and will actuate it during the upward return movement of the companion arm 61. This motion of 35 the lever 78 will be communicated to the companion numeral printing type bar 50. Thus, the rear end of each lever 78 has a pin and slot connection with a companion actuating lever 80 fulcrumed on the fulcrum bar 12 and provided with an upstanding extension 81. Said extension 40 has a pin and slot connection with a companion bell crank lever 82 that carries a pin 83 at its upper end that is received in a slot 84 in the heel of the associated type bar 50. If desired 45 the type bars 50 may have the usual cams 25 cut off or eliminated, as indicated at 85, inasmuch as the universal bar 26 is not, in the present construction, to be actuated by the numeral printing type bars, as is the case in the construction disclosed in my hereinbefore mentioned application. From the foregoing it will be understood that as each cam 52 completes the second half of its revolution, after having brought about a computing operation, the delayed printing operation of the 55 corresponding numeral printing type bar will be effected. In order however, to overcome the inertia that the use of a comparatively long and heavy, sluggishly moving, carriage entails, I provide special means for actuating the carriage 60 escapement mechanism at an earlier point in the printing stroke of a numeral printing type bar 50 than in the printing stroke of an alphabet printing type bar 11, as will now appear.

On the extension 81 of each of the numeral type 65 bar actuating levers 80 there is pivoted at 85 a one-way actuating device or pawl 87. A laterally bent lug 88 on each pawl overlies the companion extension 81 and coacts therewith to limit the movement of the pawl around its pivot 86 70 in one direction. A spring 89, connected at one end to each pawl and at the other end to a pin 90 on the companion extension, tends to normally maintain the lug 88 against the companion extension. The engaging end or nose 91 of each 75

5 pawl 87 during its downward movement is adapted to engage a flange 92 of a universal bar designated as a whole by the reference numeral 93. Said universal bar is provided with arms 94 at the ends thereof. Each arm 94 has a hub 95 fixed thereto which is tapped to receive a set screw 96. These screws secure the hubs and universal bar 93 to a rock shaft 97 suitably mounted at its ends in the frame of the machine.

10 Motion is transmitted from the rock shaft 97 to the dog rocker 34 as will now appear. A crank arm 98 has a hub 99 fixed thereto and this hub is secured by a set screw 100 to the shaft 97. Depending from the crank arm 98 are two stop 15 fingers 101 and 102 on opposite sides of an arm-resting rod 103 which is available in the present instance to coact with the stop fingers 101 and 102, although originally employed for another purpose. The upper end of the crank arm 98 is connected to one end of a contractile spring 104, the opposite end of which is anchored to a fixed plate 105. The force of this spring is exerted to return the crank arm 98 and the parts connected therewith to normal position, with the 20 stop finger 101 arrested by the rod 103.

The crank arm 98 is pivoted at 106 to a rearwardly and upwardly extending link 107; a leaf spring 108 affording a detachment of the link from said crank arm. The rear end of the link 30 107 is pivoted at 109 to a lever 110; a leaf spring 111 affording a detachment of said link 107 from the lever. The lever 110 is mounted at its lower end to turn on the pivot 46 supported by the bracket 47 and extends upward in front of a 35 lug 112 secured to and projecting laterally from the link 32. It will be understood, therefore, that a rearward actuation of the link 107 results in effecting a rearward movement of the link 32 to operate the dog rocker 34 in the same manner 40 that such link is actuated by the universal bar 26 but earlier in the printing stroke of the type bar. This is evidenced by a consideration of Fig. 1 in which the dotted line position of a numeral printing type bar 50 indicates approximately 45 the point in its printing stroke when the dog rocker is actuated under control of the universal bar 93 to afford a "let-off" of the carriage.

From the foregoing it will be understood that even though the timed relation in the operation 50 of the parts is such that a numeral printing type bar 50 is delayed until after the computing mechanism has been actuated, and the second half revolution of the associated cam 52 is taking place, the escapement mechanism will, 55 nevertheless, be operated very early in the printing stroke of such type bar, as illustrated by the dotted line showing of the type bar 50 in Fig. 1. The effect of this is to give the full time that it takes a type bar 50 to move from its dotted line 60 position in Fig. 1 to printing position to enable the carriage to overcome inertia and be set in motion. Such time is ample to compensate for the delayed operation of the type bar 50 and to overcome the difficulties hereinbefore pointed out.

65 I have hereinbefore pointed out that the stop 102 is capable of coacting with the rod 103 to arrest the actuating movement of the crank arm 98 and the parts controlled thereby, and have so shown the stop 102 in dotted lines in Fig. 7.

70 It should be understood, however, that in the

ordinary operation of the parts such actuation does not take place and that ordinarily considerably less movement is given to the universal bar 93 than is indicated in Fig. 7; the actuated pawl 87 slipping off the ledge 92 of the universal bar 93 before such bar has attained the dotted line position shown in Fig. 7, and affording an instantaneous return of the universal bar to normal position, thus completing the operating cycle required to give a full letter-space advance to the carriage. The purpose in providing the stop 102 is to limit the extreme movement of the parts they might occasionally receive in the absence of such stop by an overthrow in the action of the parts and to prevent them from ever attaining a position where a pawl 87 could coact with the flange 113 instead of with the flange 92 of the universal bar 93.

It will be understood that as a pawl 87 descends the lower end 91 thereof will engage the flange 92 and at this time the front edge of the pawl will coact with the flange 113 and the lug 88 on the pawl will be held against the extension 81, as shown in full lines in Fig. 7. As the pawl continues its descent it will carry the universal bar 93 with it and as the latter turns around its pivotal center 97 the flange 113 will turn the pawl around its pivot 86 against the force of the pawl spring 88, lifting the stop lug 88 off the extension 81, as shown in dotted lines in Fig. 7. The effect of this pivotal movement of the actuated pawl 87 around its pivot 86 is to disengage the pawl from the flange 92 and permit the instantaneous independent return of the universal bar, as pointed out above.

Various changes may be made in the construction, and parts thereof may be eliminated, without departing from my invention as it is defined in the accompanying claims.

What I claim as new and desire to secure by Letters Patent is:

1. In a power actuated combined typewriting and computing machine, the combination of a carriage, escapement mechanism therefor, numeral printing type bars, computing mechanism, power actuated means for first actuating said computing mechanism and then operating the corresponding numeral printing type bar, a universal bar actuated by a part of said last mentioned power actuated means at the beginning of the operation of said numeral printing type bar.

2. In a combined typewriting and computing machine, the combination of numeral type bars, numeral keys, a carriage, escapement mechanism for said carriage, individual cams which may be set into operation by operation of said numeral keys, a separate rocking member for each cam and controllable by its respective cam for movement from normal position to position to render it effective with relation to a respective numeral type bar and then back to normal position, and means operable by each of the rocking members for effecting a printing blow by the respective numeral type bar and for effecting operation of said escapement mechanism at the beginning of the return movement of said rocking member.

FREDERICK A. HART.

70
